CLAIM

The ornamental design for a confectionery packaging, as shown and described.

DESCRIPTION

FIG. 1 is a perspective view of a confectionery packaging, showing our new design in a first embodiment;

FIG. 2 is a front view of FIG. 1;

FIG. 3 is a rear view of FIG. 1;

FIG. 4 is a side view of FIG. 1;

FIG. 5 is another side view of FIG. 1;

FIG. 6 is a top view of FIG. 1;

FIG. 7 is a bottom view of FIG. 1;

FIG. 8 is a perspective view of a confectionery packaging, showing our new design in a second embodiment;

FIG. 9 is a front view of FIG. 8;

FIG. 10 is a rear view of FIG. 8;

FIG. 11 is a side view of FIG. 8;

FIG. 12 is another side view of FIG. 8;

FIG. 13 is a top view of FIG. 8; and,

FIG. 14 is a bottom view of FIG. 8.

The broken line disclosure forms no part of the claimed design.

The dash-dot-dash lines indicate an unclaimed boundary between the claimed subject and unclaimed subject matter.
